ABSTRACT

A convergence determination unit determines whether a state of the bucket has converged to a current target state. A target state update unit is configured to update a target state of the bucket when the convergence determination unit determines that the state of the bucket has converged to the current target state. The convergence determination unit includes a first convergence determination unit and a second convergence determination unit. The first convergence determination unit determines whether a swing angle of each mechanism has converged to the corresponding target swing angle under a first convergence condition. The second convergence determination unit determines whether a swing angle of each mechanism has converged to the corresponding target swing angle under a second convergence condition, which is stricter than the first convergence condition.

TRACK FOLLOWING SYSTEM, TRACK FOLLOWING METHOD, AND COMPUTER READABLE MEDIUM

This application is a National Stage Entry of PCT/JP2020/003103 filed on Jan. 29, 2020, which claims priority from Japanese Patent Application 2019-014687 filed on Jan. 30, 2019, the contents of all of which are incorporated herein by reference, in their entirety.

TECHNICAL FIELD

The present invention relates to a track following system, a track following method, and a computer readable medium.

BACKGROUND ART

Patent Literature 1 discloses an automatic excavation method for a hydraulic excavator for automatically throwing earth and sand into a dump truck, a crusher, or the like. Specifically, the operator first operates the hydraulic excavator and the operation is subsequently stored in the controller by teaching, and thereafter, the controller operates the hydraulic excavator instead of the operator.

CITATION LIST

Patent Literature

[Patent Literature 1] Japanese Unexamined Patent Application Publication No. H10-212740

SUMMARY OF INVENTION

Technical Problem

It is conceivable that, when the hydraulic excavator is automatically controlled, for example, the operator inputs the target track of the bucket into the control device in advance, and this control device moves the bucket along the target track. It is then conceivable that, for example, the control device sets a plurality of target points on the target track, and when it is determined that the bucket has converged near the i -th target point, the controller repeatedly updates the target state of the bucket so that the bucket moves toward the $(i+1)$ -th target point. However, there is still room for improvement regarding the above-mentioned convergence determination.

An object of the present disclosure is to provide a technique for solving any of the above-mentioned problems.

Solution to Problem

According to a first aspect of the present disclosure, there is provided a track following system configured to control an end effector to follow a target track in a work machine having a plurality of mechanisms including the end effector and at least one support unit configured to support the end effector. The track following system comprises the following: a target state update unit configured to update a target state including at least a target coordinate of the end effector; a target relative posture calculation unit configured to calculate respective target relative postures of the plurality of mechanisms based on a current target state of the end effector; a relative posture control unit configured to control relative postures of the plurality of mechanisms so that each of the relative postures of the plurality of mechanisms

2

approaches a corresponding target relative posture; and a convergence determination unit configured to determine whether a state of the end effector has converged to a current target state. The target state update unit is configured to update a target state of the end effector when the convergence determination unit determines that a state of the end effector has converged to a current target state. The convergence determination unit includes a first convergence determination unit configured to determine whether a relative posture of each mechanism has converged to the corresponding target relative posture under a first convergence condition. The convergence determination unit includes a second convergence determination unit configured to determine whether a relative posture of each mechanism has converged to the corresponding target relative posture under a second convergence condition, the second convergence condition being stricter than the first convergence condition.

According to a second aspect of the present disclosure, there is provided a track following method configured to control an end effector to follow a target track in a work machine having a plurality of mechanisms including the end effector and at least one support unit configured to support the end effector. The track following method comprises the following: a target state update step of updating a target state including at least a target coordinate of the end effector; a target relative posture calculation step of calculating respective target relative postures of the plurality of mechanisms based on a current target state of the end effector; a relative posture control step of controlling relative postures of the plurality of mechanisms so that each of the relative postures of the plurality of mechanisms approaches a corresponding target relative posture; and a convergence determination step of determining whether a state of the end effector has converged to a current target state. The target state update step updates a target state of the end effector when the convergence determination step determines that a state of the end effector has converged to a current target state. The convergence determination step includes a first convergence determination step of determining whether a relative posture of each mechanism has converged to the corresponding target relative posture under a first convergence condition. The convergence determination step includes a second convergence determination step of determining whether a relative posture of each mechanism has converged to the corresponding target relative posture under a second convergence condition, the second convergence condition being stricter than the first convergence condition.

Advantageous Effects of Invention

According to the present invention, a new technique relating to convergence determination is provided.

BRIEF DESCRIPTION OF THE DRAWINGS

FIG. 1 is a functional block diagram of a track following system. (First example embodiment)

FIG. 2 is a side view of a backhoe. (Second example embodiment)

FIG. 3 is a functional block diagram of the backhoe. (Second example embodiment)

FIG. 4 is a diagram showing an example of a target track of a bucket. (Second example embodiment)

FIG. 5 is a table showing target states and convergence conditions. (Second example embodiment)

FIG. 6 is a control flow of the backhoe. (Second example embodiment)

DESCRIPTION OF EMBODIMENTS

First Example Embodiment

First, a track following system **100** of a first example embodiment is described below with reference to FIG. 1.

The track following system **100** is a system configured to control an end effector to follow the target track in a work machine having a plurality of mechanisms including the end effector and at least one support unit for supporting the end effector. The plurality of mechanisms include an end effector and at least one support unit that supports the end effector.

The track following system **100** includes a target state update unit **101**, a target relative posture calculation unit **102**, a relative posture control unit **103**, and a convergence determination unit **104**.

The target state update unit **101** updates the target state including at least a target coordinate of the end effector.

The target relative posture calculation unit **102** calculates the respective target relative postures of the plurality of mechanisms based on the current target state of the end effector.

The relative posture control unit **103** controls the relative postures of the plurality of mechanisms so that each of the relative postures of the plurality of mechanisms approaches the corresponding target relative postures.

The convergence determination unit **104** determines whether the state of the end effector has converged to the current target state.

Then, the target state update unit **101** is configured to update the target state of the end effector when the convergence determination unit **104** determines that the state of the end effector has converged to the current target state.

Furthermore, the convergence determination unit **104** includes a first convergence determination unit **105** and a second convergence determination unit **106**.

The first convergence determination unit **105** determines whether the relative posture of each mechanism has converged to the corresponding target relative posture under a first convergence condition.

The second convergence determination unit **106** determines whether the relative posture of each mechanism has converged to the corresponding target relative posture under a second convergence condition, which is stricter than the first convergence condition.

According to the above configuration, a new technique relating to convergence determination is provided. That is, a flexible convergence determination can be achieved.

Second Example Embodiment

Next, a backhoe **1** is described below with reference to FIGS. 2 to 6. The backhoe **1** is a hydraulic excavator having a bucket that mainly faces the main body of the backhoe **1** and excavates toward the main body side. The backhoe **1** is used, for example, when the residual soil discharged from a processing apparatus by a belt conveyor and accumulated in an earth and sand pit is loaded on a dump truck. The backhoe **1** is a specific example of the work machine.

In this example embodiment, the backhoe **1** is exemplified as a work machine. However, the work machine is not limited to the backhoe **1**, and may be, for example, a loading excavator, which is a hydraulic excavator excavating toward the traveling direction, or another construction heavy

machine. Furthermore, the work machine is not limited to construction heavy machine, and may be various robots in which an end effector is supported by at least one support unit, as represented by an industrial robot, for example.

FIG. 2 shows a side view of the backhoe **1**. As shown in FIG. 2, the backhoe **1** includes a lower traveling body **2**, a swivel body **3**, a boom **4**, an arm **5**, and a bucket **6**.

The swivel body **3** is mounted on the lower traveling body **2** so as to be able to swivel horizontally.

The boom **4** is swingably supported by the swivel body **3** via a first joint **7**. The boom **4** is a specific example of a support unit configuring the mechanism.

The arm **5** is swingably supported by the boom **4** via a second joint **8**. The arm **5** is a specific example of the support unit configuring the mechanism.

The bucket **6** is swingably supported by the arm **5** via a third joint **9**. The bucket **6** is a specific example of the end effector configuring the mechanism. In this example embodiment, three mechanisms including a boom **4**, an arm **5**, and a bucket **6** are exemplified. However, the mechanism is not limited to these, and the number is not limited to three.

The swivel body **3**, the boom **4**, the arm **5**, and the bucket **6** are connected in series in the order described. Therefore, the bucket **6** is swingably supported by the swivel body **3** via the arm **5** and the boom **4** in the order described. Each of the boom **4**, the arm **5**, and the bucket **6** herein is a specific example of the mechanism, and therefore may be simply referred to as a "mechanism".

FIG. 3 shows a functional block diagram of the backhoe **1**. As shown in FIG. 3, the backhoe **1** further includes an engine **10**, a hydraulic pump **11**, a hydraulic control valve **12**, an electronic control valve **13**, a boom cylinder **14**, an arm cylinder **15**, and a bucket cylinder **16**. The backhoe **1** also includes a swivel hydraulic motor **17** and a traveling hydraulic motor **18**. In addition, the backhoe **1** includes a boom posture sensor **19**, an arm posture sensor **20**, and a bucket posture sensor **21**. The backhoe **1** further includes a track following control unit **22**.

The boom cylinder **14**, arm cylinder **15**, bucket cylinder **16**, swivel hydraulic motor **17**, and traveling hydraulic motor **18** all operate by receiving pressure oil from the hydraulic pump **11** driven by the engine **10** via the hydraulic control valve **12**. The hydraulic control valve **12** receives pilot pressure from the electronic control valve **13** and switches to supply pressure oil to the boom cylinder **14**, arm cylinder **15**, bucket cylinder **16**, swivel hydraulic motor **17**, and traveling hydraulic motor **18** as appropriate. The electronic control valve **13** switches in response to a control signal from the track following control unit **22**, and supplies the pilot pressure to the hydraulic control valve **12** to switch the hydraulic control valve **12**.

The swivel hydraulic motor **17** is a hydraulic motor for swiveling the swivel body **3**.

The traveling hydraulic motor **18** is a hydraulic motor for traveling the lower traveling body **2**.

The boom posture sensor **19** is a swing angle sensor, which detects the swing angle θ_1 of the boom **4** with respect to the swivel body **3** shown in FIG. 2 and outputs the detection result to the track following control unit **22**. Here, the swing angle θ_1 is an angle between the line segment connecting the first joint **7** to the second joint **8** of the boom **4** and the vertical direction, as shown in FIG. 2. The swing angle θ_1 means the relative posture of the boom **4**.

The arm posture sensor **20** is a swing angle sensor, which detects the swing angle θ_2 of the arm **5** with respect to the boom **4** and outputs the detection result to the track following control unit **22**. Here, the swing angle θ_2 is an angle

between the line segment connecting the second joint **8** to the third joint **9** of the arm **5** and the line segment connecting the first joint **7** to the second joint **8** of the boom **4**. The swing angle **θ2** means the relative posture of the arm **5**.

The bucket posture sensor **21** is a swing angle sensor, which detects a swing angle **θ3** with respect to the arm **5** of the bucket **6** and outputs the detection result to the track following control unit **22**. Here, the swing angle **θ3** is an angle between the line segment connecting the third joint **9** of the bucket **6** to the bucket cutting edge **6a** and the line segment connecting the second joint **8** to the third joint **9** of the arm **5**. The swing angle **θ3** means the relative posture of the bucket **6**.

The boom posture sensor **19**, the arm posture sensor **20**, and the bucket posture sensor **21** are configured with, for example, a rotary encoder. However, the boom posture sensor **19** may be configured with a sensor that detects the length of the cylinder of the boom cylinder **14** so that the track following control unit **22** may calculate the swing angle **θ1** based on the detection result of this sensor. The boom posture sensor **19** to be adopted also may be an acceleration sensor so that the track following control unit **22** may calculate the swing angle **θ1** based on the detection result of the acceleration sensor. The same applies to the arm posture sensor **20** and the bucket posture sensor **21**.

Here, with reference to FIG. 2, the relationship of the coordinates and absolute posture of the bucket cutting edge **6a** with the respective swing angles **θ1**, **θ2**, and **θ3** is described below. As shown in FIG. 2, let **x** be the X coordinate of the bucket cutting edge **6a**, let **y** be the Y coordinate thereof, and let **θ** be the absolute posture of the bucket cutting edge **6a**. The absolute posture **θ** of the bucket cutting edge **6a** is an angle between the line segment connecting the third joint **9** of the bucket cutting edge **6a** to the bucket cutting edge **6a** and the horizontal. Let **L1** be the length of the line segment connecting the first joint **7** to the second joint **8** of the boom **4**, let **L2** be the length of the line segment connecting the second joint **8** to the third joint **9** of the arm **5**, and let **L3** be the length of the line segment connecting the third joint **9** of the bucket **6** to the bucket cutting edge **6a**. Then, the X coordinate **x**, the Y coordinate **y** and the absolute posture **θ**, of the bucket **6**, are expressed by the following expressions (1) to (3), respectively. Here, the origin of the X coordinate **x** and the Y coordinate **y** of the bucket **6** is the first joint **7**.

[Expression 1]

$$x = L_1 \sin \theta_1 + L_2 \sin(\theta_1 + \theta_2) + L_3 \sin \theta_r \quad (1)$$

[Expression 2]

$$y = L_1 \cos \theta_1 + L_2 \cos(\theta_1 + \theta_2) + L_3 \cos \theta_r \quad (2)$$

[Expression 3]

$$\theta = \theta_1 + \theta_2 + \theta_3 \quad (3)$$

Therefore, the swing angles **θ1**, **θ2**, and **θ3** such that the X coordinate **x**, the Y coordinate **y**, and the absolute posture **θ** of the bucket **6** are desired values can be obtained by the following expressions (4) to (12).

[Expression 4]

$$\theta_1 = \varphi_1 \quad (4)$$

5 [Expression 5]

$$\theta_2 = \varphi_2 - \theta_1 \quad (5)$$

[Expression 6]

$$\theta_3 = \theta - \theta_1 - \theta_2 \quad (6)$$

10 [Expression 7]

$$\varphi_1 = \tan^{-1} \frac{\lambda_x}{\lambda_y} - \tan^{-1} \frac{\sqrt{\lambda_x^2 + \lambda_y^2 - \alpha^2}}{\alpha} \quad (7)$$

15 [Expression 8]

$$\varphi_2 = \tan^{-1} \frac{\lambda_x}{\lambda_y} - \tan^{-1} \frac{\sqrt{\lambda_x^2 + \lambda_y^2 - \beta^2}}{\beta} \quad (8)$$

20 [Expression 9]

$$\lambda_x = x - L_3 \sin \theta \quad (9)$$

[Expression 10]

$$\lambda_y = y - L_3 \cos \theta \quad (10)$$

25 [Expression 11]

$$\alpha = \frac{\lambda_x^2 + \lambda_y^2 + (L_1^2 - L_2^2)}{2L_1} \quad (11)$$

30 [Expression 12]

$$\beta = \frac{\lambda_x^2 + \lambda_y^2 - (L_1^2 - L_2^2)}{2L_2} \quad (12)$$

35 In the backhoe **1** of this example embodiment, in order to automatically control the bucket **6**, first, the X coordinate **x**, the Y coordinate **y**, and the absolute posture **θ**, which are the targets of the bucket **6**, are discretely determined according to the target track of the bucket **6**. Then, the swing angles **θ1**, **θ2**, and **θ3** for achieving the X coordinate **x**, Y coordinate **y**, and absolute posture **θ** of the bucket **6** are calculated, and the swing angles **θ1**, **θ2**, and **θ3** are set to controlled targets in the automatic control. Hereinafter, the X coordinate **x**, the Y coordinate **y**, and the absolute posture **θ** of the bucket **6** are referred to as the state of the bucket **6**. The target values of the X coordinate **x**, the Y coordinate **y**, and the absolute posture **θ** of the bucket **6** are expressed as the target X coordinate **xr**, the target Y coordinate **yr**, and the target absolute posture **Or**, respectively. The target values of the swing angles **θ1**, **θ2**, and **θ3** are expressed as the target swing angles **θr1**, **θr2**, and **θr3**, respectively. The subscript **r** is an acronym for reference, which means an act of looking at something for information.

40 Next, the track following control unit **22** is described below in detail with reference to FIG. 3.

45 The track following control unit **22** is a specific example of the track following system. In this example embodiment, the backhoe **1** includes a track following control unit **22**. However, the track following control unit **22** may be provided outside the backhoe **1**. The track following control unit **22** may be embodied by a single device or may be embodied by a plurality of devices. When the track following control unit **22** is embodied by a plurality of devices, the plurality of devices may be arranged at the same geographical location or at geographically separated locations.

50 The track following control unit **22** includes a CPU **22a** as a central processing unit, a freely readable and writable

RAM 22b, and a read-only ROM 22c. Then, the CPU 22a reads and executes the control program stored in the ROM 22c, so that the control program causes the hardware such as the CPU 22a to function as the target track storage unit 30. Similarly, the control program causes hardware such as the CPU 22a to function as the target state update unit 31, the target relative posture calculation unit 32, the relative posture control unit 33, and the convergence determination unit 34.

The target track storage unit 30 stores the target track of the bucket 6. FIG. 4 shows an example of the target track of the bucket 6. The target track of FIG. 4 is a track of the bucket 6 for excavating the residual soil accumulated in the earth and sand pit and accommodating it in the bucket 6. The target track of FIG. 4 is configured with a plurality of discretized target states P1 to P10 of the bucket 6. Each target state P1 to P10 includes at least the target X coordinate x_r and the target Y coordinate y_r , which are the target coordinates of the bucket cutting edge 6a of the bucket 6. In this example embodiment, each of the target states P1 to P10 further includes a target absolute posture θ_r of the bucket cutting edge 6a of the bucket 6. Therefore, in this example embodiment, each of the target states P1 to P10 of the bucket 6 is configured with the target X coordinate x_r , the target Y coordinate y_r , and the target absolute posture θ_r of the bucket cutting edge 6a of the bucket 6. The track following control unit 22 controls the swing angles θ_1 , θ_2 , and θ_3 so that the state of the bucket 6 sequentially follows the target states P1 to P10.

FIG. 5 shows a plurality of discretized target states P1 to P10 of the bucket 6. In FIG. 5, the target X coordinate x_r of the bucket cutting edge 6a of the bucket 6 corresponding to the target state P_n is represented by $x_r(n)$, the target Y coordinate y_r thereof is represented by $y_r(n)$, and the target absolute posture θ_r thereof is represented by $\theta_r(n)$. Here, n is an integer from 1 to 10.

The target state update unit 31 refers to the table shown in FIG. 5 to set the target state of the bucket 6 at the start of the following control and to update the target state of the bucket 6 as the following control progresses.

The target relative posture calculation unit 32 calculates the respective target swing angles θ_{r1} , θ_{r2} , and θ_{r3} based on the current target state of the bucket 6. The specific calculation method should be seen in the above expressions (4) to (12). In FIG. 5, the target swing angle θ_{r1} corresponding to the target state P_n is represented by the target swing angle $\theta_{r1}(n)$. The target swing angle θ_{r2} corresponding to the target state P_n is represented by the target swing angle $\theta_{r2}(n)$. The target swing angle θ_{r3} corresponding to the target state P_n is represented by the target swing angle $\theta_{r3}(n)$.

The relative posture control unit 33 controls the swing angles θ_1 , θ_2 , and θ_3 so that the swing angles θ_1 , θ_2 , and θ_3 approach the corresponding target swing angles θ_{r1} , θ_{r2} , and θ_{r3} , respectively.

Returning to FIG. 3, the convergence determination unit 34 determines whether the state of the bucket 6 has converged to the current target state. The convergence determination unit 34 includes a first convergence determination unit 35 and a second convergence determination unit 36.

The first convergence determination unit 35 determines whether the swing angle corresponding to the relative posture of respective mechanisms have converged to the corresponding target swing angles θ_{r1} , θ_{r2} , and θ_{r3} under the first convergence condition. The second convergence determination unit 36 determines whether the swing angles corresponding to the relative postures of the respective

mechanisms have converged to the corresponding target swing angles θ_{r1} , θ_{r2} , and θ_{r3} under the second convergence condition, which is stricter than the first convergence condition.

5 Here, the relative posture of the boom 4 is a swing angle θ_1 . The relative posture of the arm 5 is a swing angle θ_2 . The relative posture of the bucket 6 is a swing angle θ_3 .

In FIG. 4, the first constraint condition is imaged by a circle represented by δ_A and δ_B , and the second constraint condition is imaged by a circle represented by ϵ_A and ϵ_B . Note that the targets of the convergence determination under the first convergence condition and the second convergence condition are just the swing angles θ_1 , θ_2 , and θ_3 of the boom 4, the arm 5, and the bucket 6, respectively. It should be noted that, in FIG. 4, in order to promote understanding, the target of the convergence determination under the first constraint condition and the second constraint condition is drawn as if it were the coordinate of the bucket cutting edge 6a of the bucket 6.

10 FIG. 5 shows first threshold values δ to be used in the convergence determination under the first constraint condition and second threshold values c to be used in the convergence determination under the second constraint condition. The first threshold values δ and the second threshold values c are set for respective mechanisms and also for respective target states. The first threshold values M and the second threshold values ϵ_1 shown in FIG. 5 are threshold values to be used for the convergence determination of the swing angles θ_1 of the boom 4. Similarly, the first threshold values δ_2 and the second threshold values ϵ_2 are threshold values to be used for the convergence determination of the swing angles θ_2 of the arm 5, and the first threshold values δ_3 and the second threshold values ϵ_3 are threshold values to be used for the convergence determination of the swing angles θ_3 of the bucket 6.

15 In this example embodiment, a single first threshold value δ_1 (A) is adopted as the first threshold value δ_1 to be used in the target states P1 to P7. Similarly, a single first threshold value δ_2 (A) is adopted as the first threshold value δ_2 to be used in the target states P1 to P7, and a single first threshold value δ_3 (A) is adopted as the first threshold value δ_3 to be used in the target states P1 to P7.

20 A single first threshold value M (B) is adopted as the first threshold value M to be used in the target states P8 to P10. Similarly, a single first threshold value δ_2 (B) is adopted as the first threshold value δ_2 to be used in the target states P8 to P10, and a single first threshold value δ_3 (B) is adopted as the first threshold value δ_3 to be used in the target states P8 to P10.

25 The first threshold value δ_1 (A) is greater than the first threshold value δ_1 (B). The first threshold value δ_2 (A) is greater than the first threshold value δ_2 (B). The first threshold value δ_3 (A) is greater than the first threshold value δ_3 (B). Each first threshold value δ is a threshold value to be used for the convergence determination, and is compared with the deviation from each target value. Therefore, if the first threshold value δ is greater, the convergence determination condition is looser.

30 As described above, the first constraint condition is loosely set in the earlier stage of the target track of the bucket 6, and the first constraint condition is set strictly in the later stage thereof. This is because, when the bucket 6 excavates the earth and sand, the track of the bucket 6 is not required to have high accuracy for the bucket 6 approaching the earth and sand while the track of the bucket 6 is required to have high accuracy for the bucket 6 actually excavating it.

Returning to FIG. 5, in this example embodiment, a single second threshold value ϵ_1 (A) is adopted as the second threshold value ϵ_i used in the target states P1 to P7. Similarly, a single second threshold value ϵ_2 (A) is adopted as the second threshold value ϵ_i used in the target states P1 to P7, and a single second threshold value ϵ_3 (A) is adopted as the second threshold value ϵ_i used in the target states P1 to P7.

A single second threshold value ϵ_i (B) is adopted as the second threshold value ϵ_i used in the target states P8 to P10. Similarly, a single second threshold value ϵ_2 (B) is adopted as the second threshold value ϵ_i used in the target states P8 to P10, and a single second threshold value ϵ_3 (B) is adopted as the second threshold value ϵ_i used in the target states P8 to P10.

The second threshold value ϵ_1 (A) is greater than the second threshold value ϵ_1 (B). The second threshold value ϵ_2 (A) is greater than the second threshold value ϵ_2 (B). The second threshold value ϵ_3 (A) is greater than the second threshold value ϵ_3 (B). Each second threshold value ϵ_i is a threshold value used for the convergence determination, and is compared with the deviation from each target value. Therefore, if the second threshold value ϵ_i is greater, the convergence determination condition is looser.

The first convergence determination unit 35 determines whether the swing angles corresponding to the relative postures of the respective mechanisms have converged to the corresponding target swing angles θ_{r1} , θ_{r2} , and θ_{r3} under the first convergence condition based on the following expression (13).

[Expression 13]

$$|\theta_r^i - \theta^i| < \delta^i \quad (13)$$

In the above expression (13), the first term on the left side is the target swing angle θ_{ri} . The second term on the left side is the current swing angle θ^i of each mechanism. The right side is the first threshold value δ^i . In each case, the subscript i is an integer from 1 to 3.

The second convergence determination unit 36 determines whether the swing angles corresponding to the relative postures of the respective mechanisms have converged to the corresponding target swing angles θ_{r1} , θ_{r2} , and θ_{r3} under the second convergence condition based on the following expression (14).

[Expression 14]

$$|\theta_r^i - \theta^i| < \epsilon^i \quad (14)$$

In the above expression (14), the right side is the second threshold value ϵ^i .

The first threshold value δ is set greater than the second threshold value ϵ . That is, the first threshold value δ^i (A) is greater than the second threshold value ϵ^i (A), and the first threshold value δ^i (B) is greater than the second threshold value ϵ^i (B).

With the above configuration, when the convergence determination unit 34 determines that the state of the bucket 6 has converged to the current target state, the target state update unit 31 updates the target state of the bucket 6 so that the target state of the bucket 6 becomes the next target state.

Next, the control flow of the backhoe 1 is described below with reference to FIG. 6.

S100:

First, the target state update unit 31 sets the target state of the bucket 6 to the target state P1.

S110: Next, the target relative posture calculation unit 32 calculates the respective target swing angles θ_{r1} , θ_{r2} , and θ_{r3} of all the mechanisms based on the current target state set by the target state update unit 31.

S120:

Next, the relative posture control unit 33 starts controlling the swing angles θ_1 , θ_2 , and θ_3 of all the mechanisms so that the swing angles θ_1 , θ_2 , and θ_3 of all the mechanisms approach the corresponding target swing angles θ_{r1} , θ_{r2} , and θ_{r3} , respectively. The control of the swing angle may be changing the swing angle of the mechanism. The control of the swing angle may include changing the control speed for changing the swing angle. The change in control speed may be decreasing or increasing the control speed. The relative posture control unit 33 may decrease the control speed of the mechanism when continuously controlling the relative posture of the mechanism so that the swing angle of the mechanism, which has converged under the first convergence condition, further approaches to the corresponding target swing angle.

S130:

Next, the first convergence determination unit 35 determines whether the swing angles θ_1 , θ_2 , and θ_3 of all the mechanisms have converged to the corresponding target swing angles θ_{r1} , θ_{r2} , and θ_{r3} under the first convergence condition. If YES in S130, the first convergence determination unit 35 advances the process to S140. Contrarily, if NO in S130, the first convergence determination unit 35 advances the process to S200.

S140:

The target state update unit 31 determines whether there is the next target state. If NO in S140, the track following control unit 22 ends the processing. Contrarily, if YES in S140, the target state update unit 31 advances the process to S150.

S150: The target state update unit 31 updates the target state of the bucket 6 to the next target state, and returns the process to S110.

S200-S250:

The processes from S210 to S230 are executed independently for each mechanism i . Each of the processes in S200, S240, and S250 is a loop processing for execution of processing independently for each mechanism i . The mechanism 1, the mechanism 2, and the mechanism 3 correspond to the boom 4, the arm 5, and the bucket 6, respectively.

S210:

The first convergence determination unit 35 determines whether the swing angle θ^i of the mechanism i has converged to the target swing angle θ_{ri} under the first convergence condition. If YES in S210, the first convergence determination unit 35 advances the process to S220. Contrarily, if NO in S210, the first convergence determination unit 35 advances the process to S240.

S220:

The second convergence determination unit 36 determines whether the swing angle θ^i of the mechanism i has converged to the target swing angle θ_{ri} under the second convergence condition. If YES in S220, the second convergence determination unit 36 advances the process to S230. Contrarily, if NO in S220, the second convergence determination unit 36 advances the process to S240.

S230:

The relative posture control unit 33 decreases the control speed of the swing angle θ^i of the mechanism i and stops the control of the swing angle θ^i .

S240:

When the processes from **S210** to **S230** are executed for all the mechanisms i in **S240**, the track following control unit **22** returns the processes to **S130**.

According to the processes from **S210** to **S230**, the relative posture control unit **33** controls in the following manner when preconditions (1) and (2) described below are satisfied. That is, the relative posture control unit **33** continuously controls the swing angle of the mechanism so that the swing angle of the mechanism, which has already converged to the corresponding target swing angle under the first convergence condition, further approaches the corresponding target swing angle. The precondition (1) is that the swing angle of at least one of the mechanisms has converged to the corresponding target swing angle under the first convergence condition. The precondition (2) is that the swing angle of at least one of the other mechanisms has not converged to the corresponding target swing angle under the first convergence condition. The above control can smooth the operation of the boom **4**, the arm **5**, and the bucket **6**, of the backhoe **1**. The reason is as follows.

The timing at which the swing angles of the plurality of mechanisms converge to the corresponding target swing angles under the first convergence condition usually differs from each other. Therefore, if an individual mechanism has the speed decreased and then is stopped as soon as the swing angle converges to the corresponding target swing angle under the first convergence condition, what takes place is the following: the mechanism whose swing angle has converged to the target swing angle before the other mechanisms must stand by with the angle change in the swing angle set to zero until the swing angles of all the other mechanisms converge to the target swing angles under the first convergence conditions. In other words, it is necessary to temporarily stop the change in the joint angle between the mechanisms. If the change in the joint angle between the mechanisms is temporarily stopped in this way, the change and the stop are repeated, and the operation of the boom **4**, the arm **5**, and the bucket **6** of the backhoe **1** becomes awkward.

In contrast, in this example embodiment, the angle change is not immediately decelerated and stopped when the swing angle of an individual mechanism converges to the corresponding target swing angle under the first convergence condition, which results in as follows: the angle change in the swing angle of the mechanism, the swing angle of which has converged to the target swing angle under the first convergence condition before the other mechanisms, is maintained after the convergence as well. In other words, it is less necessary to temporarily stop the change in the joint angle between the mechanisms. This can smooth the operation of the boom **4**, the arm **5**, and the bucket **6** of the backhoe **1**.

The above-described second example embodiment has the following features.

The track following control unit **22** (track following system) controls the bucket **6** to follow the target track in the backhoe **1** (work machine) provided with a plurality of mechanisms. The plurality of mechanisms include a bucket **6** (end effector), and a boom **4** and an arm **5** that support the bucket **6** (at least one support unit). The track following control unit **22** includes a target state update unit **31**, a target relative posture calculation unit **32**, a relative posture control unit **33**, and a convergence determination unit **34**. The target state update unit **31** updates the target state including at least the target coordinates of the bucket **6**. The target relative posture calculation unit **32** calculates each of the target swing angles (target relative postures) of the plurality of

mechanisms based on the current target state of the bucket **6**. The relative posture control unit **33** controls the swing angles of the plurality of mechanisms so that each of the swing angles (relative postures) of the plurality of mechanisms approaches the corresponding target swing angle. The convergence determination unit **34** determines whether the state of the bucket **6** has converged to the current target state. The target state update unit **31** is configured to update the target state of the bucket **6** when the convergence determination unit **34** determines that the state of the bucket **6** has converged to the current target state. The convergence determination unit **34** includes a first convergence determination unit **35** and a second convergence determination unit **36**. The first convergence determination unit **35** determines whether the swing angle of each mechanism has converged to the corresponding target swing angle under the first convergence condition. The second convergence determination unit **36** determines whether the swing angle of each mechanism has converged to the corresponding target swing angle under the second convergence condition, which is stricter than the first convergence condition. According to the above configuration, a new technique relating to convergence determination is provided. That is, a flexible convergence determination can be achieved.

In addition, the convergence determination unit **34** determines that the state of the bucket **6** has converged to the current target state when the swing angles of all the mechanisms have converged to the corresponding target swing angles under the first convergence condition.

Furthermore, when the swing angle of at least one of the mechanisms has converged to the corresponding target swing angle under the first convergence condition, and when the swing angle of at least one of the other mechanisms has not converged to the corresponding target swing angle under the first convergence condition, the relative posture control unit **33** does the following: continuously controlling the swing angle of the mechanism so that the swing angle of the mechanism, which has already converged to the corresponding target swing angle under the first convergence condition, further approaches the corresponding target swing angle. According to the above configuration, the operation of each mechanism can be smoothed.

Then, the relative posture control unit **33** stops the control of the swing angle of each mechanism when the swing angle of each mechanism converges to the corresponding target swing angle under the second convergence condition.

In addition, the target state of the bucket **6** further includes the target absolute posture of the bucket **6**.

A track following method includes a target state update step (**S150**), a target relative posture calculation step (**S110**), a relative posture control step (**S120**), and a convergence determination step (**S130**, **S210**, **S220**). The target state update step (**S150**) updates the target state of the bucket **6** when the convergence determination step determines that the state of the bucket **6** has converged to the current target state (**S130**: YES). The convergence determination step (**S130**, **S210**, **S220**) includes a first convergence determination step (**S210**) and a second convergence determination step (**S220**). The first convergence determination step (**S210**) determines whether the swing angle of each mechanism has converged to the corresponding target swing angle under a first convergence condition. The second convergence determination step (**S220**) determines whether the swing angle of each mechanism has converged to the corresponding target swing angle under a second convergence condition, which is stricter than the first convergence condition. According to the above method, a new technique relating to determining

13

convergence is provided. That is, a flexible convergence determination can be achieved.

In the above example, the program can be stored using various types of non-transitory computer readable media, and can be supplied to a computer. Non-transitory computer readable media include various types of tangible storage media. Examples of non-transitory computer readable media include magnetic recording media (for example, flexible disks, magnetic tapes, hard disk drives), magneto-optical recording media (for example, magneto-optical disks). Examples of non-transitory computer readable media further include CD-ROMs (Read Only Memories), CD-Rs, CD-R/Ws, and semiconductor memories (for example, mask ROMs). Examples of non-transitory computer readable media further include PROMs (Programmable ROMs), EPROMs (Erasable PROMs), flash ROMs, RAMs (random access memories). The program may also be supplied to the computer by various types of transitory computer readable media. Examples of transitory computer readable media include electric signals, optical signals, and electromagnetic waves. The transitory computer readable media can supply the program to the computer via wired communication paths such as electric wires and optical fibers, or wireless communication paths.

Although the invention of the present application is described above with reference to the example embodiments, the invention of the present application is not limited to the above. In the configuration and details of the invention of the present application, various changes that can be understood by those skilled in the art can be made within the scope of the invention.

This application claims the priority based on Japanese Patent Application No. 2019-014687 filed on Jan. 30, 2019, and incorporates its disclosures herein in its entirety.

REFERENCE SIGNS LIST

- 100 track following system
- 101 target state update unit
- 102 target relative posture calculation unit
- 103 relative posture control unit
- 104 convergence determination unit
- 105 first convergence determination unit
- 106 second convergence determination unit

What is claimed is:

1. A track following system configured to automatically control an end effector to follow a target track in a work machine having a plurality of mechanisms including the end effector and at least one support member configured to support the end effector, the target track being configured with a plurality of discretized target states of the end effector, each target state including at least a target coordinate of the end effector, the track following system comprising:

a processor; and
a memory storing instructions executable by the processor

to:

set a current target state of the end effector;
calculate respective target relative postures of the plurality of mechanisms based on the current target state of the end effector;

control relative postures of the plurality of mechanisms so that the relative posture of each of the plurality of mechanisms approaches a corresponding target relative posture;

determine whether a state of the end effector has converged to the current target state; and

14

change the current target state of the end effector so that the current target state is set to a next target state according to the plurality of discretized target states of the end effector, the plurality of discretized target states defining the target track, when the state of the end effector has been determined to have converged to the current target state, wherein

determination of whether the state of the end effector has converged to the current target state includes:

determination of whether the relative posture of each of the plurality of mechanisms has converged to the corresponding target relative posture under a first convergence condition; and

determining of whether the relative posture of each of the plurality of mechanisms has converged to the corresponding target relative posture under a second convergence condition that is stricter than the first convergence condition.

2. The track following system according to claim 1, wherein the state of the end effector is determined to have converged to the current target state when the relative postures of all the mechanisms have converged to the corresponding target relative postures under the first convergence condition.

3. The track following system according to claim 2, wherein, when the relative posture of a first mechanism of the mechanisms has converged to the corresponding target relative posture under the first convergence condition, and when the relative posture of a second mechanism of the mechanisms has not converged to the corresponding target relative posture under the first convergence condition, the relative posture of the first mechanism that has converged under the first convergence condition is continuously controlled so that the relative posture of the first mechanism further approaches the corresponding target relative posture.

4. The track following system according to claim 1, wherein control of the relative posture of any mechanism is stopped when the relative posture has converged to the corresponding target relative posture under the second convergence condition.

5. The track following system according to claim 1, wherein the target state of the end effector further includes a target absolute posture of the end effector.

6. A track following method for automatically controlling an end effector to follow a target track in a work machine having a plurality of mechanisms including the end effector and at least one support member configured to support the end effector, the target track being configured with a plurality of discretized target states of the end effector, each target state including at least a target coordinate of the end effector, the track following method performed by a computer and comprising:

setting a current target state of the end effector;
calculating respective target relative postures of the plurality of mechanisms based on the current target state of the end effector;

controlling relative postures of the plurality of mechanisms so that the relative posture of each of the plurality of mechanisms approaches a corresponding target relative posture;

determining whether a state of the end effector has converged to the current target state; and

changing the current target state of the end effector so that the current target state is set to a next target state according to the plurality of discretized target states of the end effector, the plurality of discretized target states defining the target track, when the state of the end

15

effector has been determined to have converged to the current target state, wherein determining whether the state of the end effector has converted to the current target state includes: determining whether the relative posture of each of the plurality of mechanisms has converged to the corresponding target relative posture under a first convergence condition; and determining whether the relative posture of each of the plurality of mechanisms has converged to the corresponding target relative posture under a second convergence condition that is stricter than the first convergence condition.

7. A non-transitory computer readable medium storing a program for causing the computer to execute the track following method according to claim 6.

16
